PISTON EXPANDER

Claud C. Craven, Kansas City, Mo., assignor to
A. B. Chance Co., a corporation

Application March 23, 1936, Serial No. 70,243

2 Claims. (Cl. 309—12)

This invention relates to piston expanders and particularly to a piston skirt expander wherein a resilient member is adapted to exert pressure in opposite directions against the marginal walls of the split of a piston skirt.

The principal object of this invention is the provision of a unitary structure adapted to engage and force apart the marginal edges of the slot formed in the skirt of a piston whereby said skirt is expanded.

Another object of the invention is the provision of a resilient, U-shaped piston expander having a transversely disposed lug adjacent each of the free ends thereof formed to project into and securely engage the marginal edges of a slot formed in the piston skirt.

Other objects of the invention are economy and simplicity of construction, ease of installation, and the provision of means whereby the expander securely engages the skirt.

With these and other objects which will appear during the course of the specification in view, reference will now be had to the drawing, wherein:

Figure 1 is a front elevation of a piston expander embodying this invention.

Fig. 2 is a side elevation of the same.

Fig. 3 is an outside view of a portion of the skirt of a piston, showing the expander in the operative position.

Fig. 4 is a vertical section, taken on line IV—IV of Fig. 3.

Fig. 5 is an inside elevation of a portion of the piston skirt, showing the expander in the operative position, and,

Fig. 6 is a fragmentary, cross sectional view taken on line VI—VI of Fig. 3.

Like reference characters designate similar parts throughout the several views, and the numeral 10 represents a portion of the skirt of a piston, provided with a slit or slot 12 that extends from the open end of the skirt to a point adjacent the sealing portion or head of the piston. The margins or side walls 14 of the slit 45 are provided with oppositely disposed receiving orifices 16 which are substantially symmetrical at opposite sides of the slit. These orifices combine to produce a substantially frusto-conical hole through the skirt, with the larger cross-sectional area at the outside thereof, thus forming inwardly converging side walls for reasons hereinafter set forth.

Referring now particularly to the expander which is shown in its normal form in Figs. 1 and 55 2, it will be observed that it comprises a single

strip of resilient sheet metal 18 which is rebent upon itself into a substantially U-shaped body portion 20, the arms 22 of which are slightly bowed inwardly as at 24. Extending in like direction and in transverse relation to 20, adjacent the free end of each of the arms 22, is a lug 26. Each lug is substantially semi-circular in cross section and semi-frusto-conical in a plane perpendicular to arm 22.

With reference to Figs. 3, 4, 5 and 6, in which 10 the expander is shown in the operative position in the piston skirt, it will be noted that these lugs 26 are adapted to be fitted into orifice 16 so as to conform to the inner walls thereof in such a manner as to preclude any accidental removal of 15 the expander from its operative position. When the expander is to be positioned in the opening formed through the skirt, the arms 22 are compressed sufficiently to allow the lugs to be introduced from the inside of the piston through 20 the small side of the opening, after which they are permitted to be forced outwardly against the side walls by the action of the tension set up in the body of the expander. When so positioned, points 24 of the two arms will be in contact, 25 thereby shortening the fulcrum lever of lugs 26 to produce a much greater pressure against the opposite walls of slit 12 than could be obtained with the fulcrum at the closed end of the U-shaped body portion.

As a further means to facilitate proper tensioning of the lugs for expanding the piston skirt, arms 22 are tapered from their greatest width at the closed end of body 20 to their narrowest width at their free end. That portion 28 at the 35 free end of each of the arms which extends beyond lugs 26 serves to contact the inner wall of the piston skirt to prevent undesirable rocking of the body portion.

The undercut relation of the lugs and the side 40 walls of the conical hole in the skirt of the piston is such that it becomes necessary to compress the outer ends of arms 22 to a considerable degree before the expander can be released from its operative position. This feature is very important and insures the proper relation of parts 45 without danger of the expander becoming dislodged to cause interference with the proper action of the piston within the cylinder.

While I have shown the arms contacting at 24 50 in the drawing, it would be possible to so construct the resilient portion of the expander so as to produce the exact tensions necessary to obtain proper expansion under all circumstances.

Having thus described the invention, what I 55

claim as new and desire to secure by Letters Patent is:

- 5 1. In combination; a piston comprising a head portion and a skirt having a longitudinal slot therein forming opposed edge faces, each of said faces having a notch therein extending transversely of said longitudinal slot, said notches being in opposed relation and combining to create a frusto-conical orifice through the skirt of the piston with its largest diameter at the outer face of the skirt; and a sheet metal expander comprising a resilient U-shaped body adapted to exert expanding force against the opposed edge faces of the skirt, said body having a laterally extending lug on one edge of said body adjacent to each free end thereof, the remote faces of said lugs combining to present a frusto-conical surface engageable with the said orifice of like form when the expander is in the operative position.
- 10 15 2. In combination; a piston comprising a head portion and a skirt having a longitudinal slot

therein forming opposed edge faces, each of said faces having a notch therein extending transversely of said longitudinal slot, said notches being in opposed relation and combining to create a frusto-conical orifice through the skirt of the piston with its largest diameter at the outer face of the skirt; and a sheet metal expander comprising a resilient U-shaped body adapted to exert expanding force against the opposed edge faces of the skirt, said body having a laterally extending lug on one edge of said body adjacent to each free end thereof, the remote faces of said lugs combining to present a frusto-conical surface engageable with the said orifice of like form when the expander is in the operative position, 15 said lugs being in opposed relation and spaced inwardly from the free ends of said U-shaped body whereby to prevent rocking movement of the body toward and from the skirt of the piston.

CLAUD C. CRAVEN.
